L. G. Willcox

H. W. Simms INVENTOR.

BY

Geo. R. Willcox ATTORNEY.

UNITED STATES PATENT OFFICE.

HENRY W. SIMMS, OF BAY CITY, MICHIGAN.

LUBRICATOR.

SPECIFICATION forming part of Letters Patent No. 674,127, dated May 14, 1901.

Application filed October 1, 1900. Serial No. 31,639. (No model.)

To all whom it may concern:

Be it known that I, HENRY W. SIMMS, a citizen of the United States, residing at Bay City, in the county of Bay and State of Michigan, have invented certain new and useful Improvements in Lubricators; and I do hereby declare the following to be a full, clear, and exact description of the invention, such as will enable others skilled in the art to which it appertains to make and use the same.

My invention relates to lubricators or grease-cups; and the improvements consist in certain constructions and combinations of parts whereby the various objects of my invention are accomplished. These objects are, first, to provide a cup for feeding grease or other viscous substances, having a plunger mounted for progressive longitudinal movement on a swiveled screw and a secondary tube or port passing through the plunger to keep it from turning and adapted to feed oil, cooling-water, or other liquid to the bearing independent of the grease-cup feed; secondly, to provide an oil-feeding tube passing through the body of the grease-cup and adapted to engage the bearing, thereby locking the cup against turning; thirdly, to provide a cover for said cup, carrying a screw-plug or equivalent device adapted to engage the upper end of the secondary tube, and thereby lock the cover against turning. I accomplish these objects by the means illustrated in the accompanying drawings, throughout the several views of which similar characters of reference designate corresponding parts.

Figure 1 is a vertical sectional view of my improved cup. Fig. 2 is a bottom view.

As is clearly shown in the drawings, the device consists in a shell 1, fitted with a removable cover 2, in which is swiveled a central screw 3, turning loosely in the cover without advancing. A plunger 4 is threaded on the screw to force the contents of the cup out through the opening 1^a. The plunger is prevented from turning while the screw rotates by a secondary tube 5, that passes by a sliding fit through the plunger and is screwed through the bottom of the cup, projecting below it. The lower end of the tube 5 enters a hole provided in the bearing near the hole into which the nipple 1^b of the cup is screwed.

The tube 5 serves the triple purpose of a lock to prevent the plunger from turning, a means to lock the cup against unscrewing, and a conduit through which oil, cleansing solutions, &c., can be injected into the bearing in case of heating of the journal or other mishap. In the cover 2 I provide a screw-cap 2^a, having a cupped end 2^b or a suitable projection to engage the upper end of the secondary tube 5. This cap serves a double purpose. It effectually prevents the cover 2 from turning or unscrewing, and it forms a means by which oil may be readily inserted into the tube 5 without disturbing the cup-cover 2.

Cups that are subjected to much jarring may be provided, if desired, with a ratchet 6, secured to the handle, and a pawl 6^a, secured to the cover and engaging with the ratchet, thereby preventing the screw from rotating backward.

The upper end of the tube 5 is preferably provided with a slot 5^a to admit of screwing it down with a screw-driver.

To attach the lubricator to the journal-box 75 of the machine on which it is to be used, the nipple 1^b of the cup is first screwed into the hole provided for it and the cup is turned so the tube 5 registers with the hole provided for it in the journal-box. The tube is then 80 screwed down until it enters the hole, thus effectually locking the cup in position on the journal-box and rendering it impossible to unscrew or jar loose. The cup having been filled with grease or similar lubricant the 85 screw 3 and plunger 4 are inserted into the cup and the cover 2 is screwed on. The cover is turned to the position where the tube 5 registers with the hole provided in the cover for the cap 2^a, and the cap is then screwed down, 90 securely locking the cover against turning.

By the above means I provide a cup that is simple, strong, self-locking, and capable of feeding either oil, grease, or cleansing solution to the bearing independent of the screw-feed and without removing either the cup or its cover 2 from the journal-box. The structural details of the cup-body may be varied at pleasure without departing from my invention.

What I claim is—

1. In a lubricator having a central screw

and a plunger traveling thereon; a tube extending the length of the cup, through the plunger, and through the bottom of the cup at the side of the discharge-nipple for entering a hole in the journal-box, thereby locking the cup against turning, and also forming a conduit for fluid to the journal, independent of the main feed.

2. In a lubricator having a traveling plunger; a tube located on one side of the center of and passing through the plunger to prevent it from turning, yet permitting its progressive movement along the axis of the cup, and forming a conduit for fluid through the cup, independent of the main feed.

3. In a lubricator, in combination with the cup; a tube extending the length of the cup and projecting through its bottom at one side of the axis; of the removable cover for the cup, and a cap removably secured in the cover above the tube, said cap being adapted to

close the tube and lock the cover against turning.

4. In a lubricator having a traveling plunger; the combination of a tube extending the length of the cup, through the plunger at one side of the axis, thereby locking the plunger against turning yet permitting its progressive longitudinal movement, and extending through the bottom of the cup, below which it projects; the cover of the cup provided with a hole registering with said tube; and a cap removably inserted in the hole and adapted to engage the upper end of the tube, thereby closing the tube and locking it against turning. 35

In testimony whereof I affix my signature in presence of two witnesses.

HENRY W. SIMMS.
